DOOR CONSTRUCTION

Charles H. Widman, Detroit, Mich., assignor to
The Murray Corporation of America, a cor-
poration of Delaware

Application September 6, 1932, Serial No. 631,815

4 Claims. (Cl. 296—44)

One object of my invention is to provide a novel construction for metal vehicle doors composed of a minimum number of parts so arranged in their relation to one another that the construction may be accomplished more cheaply than conventional constructions.

Another object of my invention is to provide a construction for a metal vehicle door, having a window opening in its upper portion, wherein expensive flanging operations heretofore necessary to the formation of the door around the window opening may be eliminated, and the necessary bending and forming of the metal around the window opening accomplished more cheaply than has been possible heretofore.

Another object of my invention is to provide a metal door for a vehicle having a window opening in its upper portion, wherein the side and top members of the door surrounding the window opening may be formed as a unit of one piece of material and applied as such to the remainder of the door parts, thereby eliminating the supplemental or additional framing or finishing members that have commonly been used in such constructions heretofore.

With these and other objects in view, my invention consists in the construction, combination and arrangement of parts set forth and claimed in the following specification and illustrated in the accompanying drawings in which:

Figure 1 is an elevational view of the outer side of the upper portion of a metal vehicle door embodying my invention and having parts broken away to better illustrate the construction;

Figure 2 is a cross-sectional view taken on the line 2—2 of Figure 1;

Figure 3 is a cross-sectional view taken on line 3—3 of Figure 1;

Figure 4 is a cross-sectional view taken on the line 4—4 of Figure 1;

Figure 5 is a cross-sectional view taken on the line 5—5 of Figure 1;

Figure 6 is a sectional view taken on the line 6—6 of Figure 2;

Figures 7 and 8 are modifications of the construction and joint illustrated in Figure 6;

Fig. 9 is a side elevational view of part of a door, having parts broken away, and illustrating a modified form of joint between the upper and lower parts of the door;

Fig. 10 is a cross-sectional view taken on line 10—10 of Fig. 9;

Fig. 11 is a cross-sectional view taken on line 11—11 of Fig. 9;

Fig. 12 is a cross-sectional view taken on line 12—12 of Fig. 9; and

Fig. 13 is a cross-sectional view taken on line 13—13 of Fig. 10.

The construction illustrated comprises generally, an inner panel member extending from the bottom of the window opening to the bottom of the door having its edges along the sides and bottom laterally flanged and extending at right angles to the plane of the panel to form the jamb or width of the door. In the construction shown, the outer edge of this lateral flange is bent over to provide a door overlapping flange or stop in the usual manner. This inner panel constitutes the margin framing of the door below the window opening and also the box section which provides the well into which the vertically sliding window may be lowered. An outer or finish panel is also provided, which consists of a single piece of sheet metal having its edges extended to provide a door overlapping flange or stop, and secured to the corresponding edges of the inner panel. The sides and top of the door around the window opening are formed of a single piece of sheet metal which may be rolled or stamped to shape as desired, and which is bent to a generally U-shaped form and is secured at its ends by butt or lap welding or other suitable means in relation to the upper edge of the inner and outer panel members at their upper corners. This top member forms a continuation of the outside panel, and when welded or similarly secured to the upper edges of this panel, is flush therewith and the joint may be worked over so that it is not visible. By so forming the members of the door as described, it is possible to eliminate expensive equipment and operations now essential to the formation of the outer panel.

It is the present custom to make the outer panel for the door, from top to bottom and around the window opening, from a single piece of sheet metal which is formed to shape by stamping. In the first stamping operation it is customary to shear out the window opening and to partly bend in the edges of the panel around the window opening. It is then necessary to perform another stamping operation, which necessitates another press and other dies, for the purpose of completely "flanging-in", as it is termed, the edges of the metal panel around the window opening to provide the ornamental shape around the window opening for what is known as the "window reveal", and also to provide a rabbeted seat for the edges of the window glass which is later installed, and which slides vertically in the plane

of the door. The flanging-in dies used in this second stamping operation are expensive, and separate operations and press machines are necessary in order to perform this work.

5 In the present invention, I have devised a construction which eliminates the necessity for these flanging-in dies, the press necessary to operate them, and the necessary separate operation upon the entire outer panel. This is accomplished by 10 making the outer panel of the door in two pieces. First, a piece which extends from the bottom of the window opening to the bottom of the door, and second, a piece which forms the sides and top of the door around the window opening and which 15 may be butt or lap welded or otherwise suitably attached to the upper edge of the first piece. This part which extends around the sides and top of the window opening may be made from a narrow strip of steel and it may be either rolled or 20 stamped to shape in a single operation. As all of the flanging-in work performed by the flanging-in dies and press, above mentioned, is performed upon this part of the door, which I form in a separate piece in a single operation by rolling or 25 stamping, the separate flanging-in operation around the door is eliminated, and the equipment necessary to so operate upon the entire panel, is likewise eliminated, or substituted for by rolling equipment, or stamping equipment 30 necessary to form the separate piece which I employ, which may be furnished and operated at less cost. It may be desired at times to perform a stamping operation on the piece after it has been 35 rolled substantially to final form, for the purpose of providing a sweep or curve to the line of the piece which can not be accomplished by the rolling operation. This can be accomplished without prohibitive increase in cost.

40 This construction also eliminates the necessity for the extension of the inside panel around the sides and top of the window opening as is now customary, as the top piece of the outside finish panel, when bent to shape, and attached to the lower part, as described, is of sufficient strength 45 and rigidity to perform the required function of framing for the upper part of the door.

45 This construction also results in a saving of metal in that it eliminates the salvage metal which is cut out of the window opening when the outer panel is formed of one piece of sheet metal, and makes it possible to utilize narrow strips of salvage metal or to more completely utilize stock sheets of metal as the only salvage in this operation would be the trimming off of comparatively 55 small margins.

50 Referring now to the drawings, the numeral 10 indicates the outer panel which extends from the bottom of the window opening 11 to the bottom of the door, not shown. The side and bottom 55 margins of this panel are extended to form door overlapping flanges or stops as indicated at 12 in Figure 5 and are bent around and secured to the corresponding flanges 13 formed on the margins of the inner panel 14. As previously 60 stated, the side and bottom edges of the inner panel 14 are flanged at substantially right angles to the plane of the inner panel as at 15, Figure 5, and provide the width or jamb of the door.

65 Both the inner and outer panel are flanged 70 inwardly toward one another along the bottom of the window opening indicated by the line 11 in Figure 1, and also shown in the lower part of Figure 2, but are spaced from one another to permit the passage of the vertically sliding window glass 16, shown in the lower part of Figure 2.

The upper corners of the inner and outer panels are extended upwardly, somewhat above the line 11 as indicated at 17 and 18 in Figure 1, to provide the radii 20 and 21 in the lower corners of the window opening. The inner margin of the outer panel along the window opening, is turned inwardly and bent as shown in Figures 2 and 4. The inner panel flange 15 above the section line 5-5 is bent to the shape shown in Figure 4, and below the section line 5-5 is of the shape shown in Figure 5. The inner margin of the outer panel 10 is bent as shown in Figure 4 above the sectional line 4-4 and conforms substantially to the shape of the inner panel at that point. The upwardly projecting corners of the inner and outer panels 17 and 18 extend just far enough to include the radii 20 and 21 in the lower corners of the window opening, and this may be omitted if sharp window corners instead of rounded ones are desired. The top member 25 which forms 15 the sides and top of the door around the window opening is formed of a single piece of sheet metal either rolled or stamped, or both, to the desired shapes, as shown in Figures 2 and 3.

20 The cross-sectional configuration of this top member corresponds to the cross-sectional configuration of the inner and outer panel members at the points 17 and 18, and, in the forms shown in Figs. 1 to 6, is butt welded to the upper edges of the inner and outer panels 10 and 15 at the 25 points 17 and 18. This provides a strong and smooth exterior joint so that the outer panel 10 and the upper member 25 appear to be formed from the same piece of sheet metal.

30 As illustrated in Figures 2 and 3, the outer margin of the member 25 is extended and bent upon itself to provide a door overlap flange or stop 26, and the inner margin is extended inwardly and return bent to form a rabbeted seat 27 for the window glass channel 28 which receives, in sliding engagement, the edges of the window glass. The inner margin of the member 25 extends inwardly, substantially the width of the door, and an inside garnish molding 29 is seated upon the inner margin as shown in Figures 2 and 3, and may be secured to the member 25 at intervals, by means of metal screws 30 or other suitable means. The part of the garnish molding 29 which extends across the bottom of the window opening along the top edge of the 35 inner panel 14 has its outer surface substantially flat, as shown in Figure 2 at 31, with its inner margin turned down to clamp the top edge of the upholstery or rim 32, and its outer edge turned down at 33 over the edge of the top flange 34 on 40 the inner panel 14. As shown, the garnish molding 29 along the sides and top of the window, has its inner margin bent as at 36 to provide a side wall or support for the inner side of the glass run channel 28.

45 It will be noted that the member 25 as formed, provides a trough 35 immediately behind the overlap flange 26 and which will receive and carry down the edges of the door, any water leaking behind the flange 26 and prevent the entry of any 50 such water into the inside of the body.

55 Figures 6, 7 and 8 illustrate the joint between the ends of the member 25 and the upper corners of the inner panel flange 15 and the outer panel 10. As shown in Figure 6 at 40, the ends of the 60 member 25 may be butt welded directly to the upper edge of the panel 10. As shown in Figure 7 at 41, the edge of the member 25 may be flanged inwardly to provide a broader bearing surface and seat upon and be welded to the top edges of 65 70 75

both parts 10 and 15. As shown in Figure 8, the upper edge of the part 10 may be bent over to form a flange 42 which extends over the upper edge of the part 15 and the end of the member 25 may be bent to form a flange 43 which rests upon this and is welded to the flange 42. The flange 42 in this case being also preferably welded to the upper edge of the part 15.

In Figs. 9 to 13 I have illustrated a cap joint 10 between the upper panel member 25 and the lower panels 10 and 14.

The lower ends of the member 25 are offset inwardly as at 60 and extended downwardly as at 61, Fig. 13, and the flange 61 is spot welded 15 to the flange 15 of the lower inner panel 14, leaving a flush exterior joint at 62 between the upper panel 25 and the lower outer panel 10. This joint may be filled with solder or filed 20 smooth for complete concealment if desired. The door overlap flange or stop 26 at this joint 25 may be handled as follows. At the lower end of the overlap flange 26 on the upper panel 25 the rounded and return bent margin is cut away along the edge of the offset portion 61 so that such offset portion 61 may overlap and lay along 30 the rear side of the door overlap flange 13 (Fig. 5) formed on the inner panel 14 as shown in Figs. 11 and 13. This permits the end of the rounded and return bent portion of the door overlap 35 flange 26 on the panel 25 just above the offset flange 61 to abut the end of rounded and return bent door overlap flange on lower outer panel 10 and make a flush joint therewith. The return bent portion of the door overlap 26 on the lower panel 10 is cut away at this point, as at 63, Fig. 11, to provide room for the offset flange 61 on the panel 25, and to eliminate the extra thickness of metal which would otherwise occur at this point.

Referring now to Fig. 3, I have illustrated a reinforcing member 70 for the upper panel 25. This member is optional, and may be continuous throughout the length of member 25, or only at spaced intervals, such as points where it is desired to fasten the wing plates of hinges (not shown) to the door. The reinforcing member consists of a separate metal plate laid along the rear side of the panel 25 as shown in Fig. 3 and secured thereto by spot welding. The outer edge of the member 70 may be inserted in the return bent portion of the overlap flange 26 as shown and secured by spot welding.

It will be noted in the drawings that there is some variation in the thickness of the metal employed in the members 10, 14 and 25. This may be as desired. All parts may be of the same

thickness or they may be of different thicknesses without affecting the operation and utility of the invention.

In Figures 3 and 5 it will be noted that portions of the door post in the vehicle body are shown 5 for purposes of illustration and are indicated by the numeral 50.

It will be understood that, while the description of the joint and method of joining the upper and lower panel members referred to only one of 10 the joints, that it applies also to the other joint.

Formal changes may be made in the specific embodiment of the invention described without departing from the spirit and substance of the broad invention, the scope of which is com- 15 mensurate with the appended claims.

What I claim is:

1. In a metal vehicle door, outer and inner panels extending to form the ledge of a window opening, a complete finish and framing member 20 for said door as an independent element disposed to form the sides and top of the window opening and comprising a metal finish panel bent to provide a door overlap flange along its outer margin, an outside window reveal along its 25 intermediate portion, and a rabbeted seat for a window glass channel along its inner margin, and also providing a seat for a garnish molding along its inner margin and inwardly of said window glass channel seat. 30

2. A door constructed of independent upper and lower portions, the lower portion embodying stamped sheet metal elements terminating substantially at the window ledge, and an independent preformed strip of predetermined cross 35 section secured to said lower portion and forming the upper side and top of the door and defining a window opening therein.

3. A door constructed of independent upper and lower portions, the lower portion comprising 40 a box section element terminating substantially at the window ledge, and the upper portion including an independent preformed strip of inverted U-shape secured to said elements to form the upper sides and top of the door which defines a window opening. 45

4. A door constructed of independent upper and lower portions, the lower portion comprising a box section element preformed at its top edge to constitute a window ledge, the upper portion comprising an independent preformed strip of inverted U-shape secured to said element to form the upper sides and top of the door and to define a window opening. 50

CHARLES H. WIDMAN. 55
